CLAIM

The ornamental design for a handle for a multifunction printing machine, as shown and described.

DESCRIPTION

FIG. 1 is a perspective view of a handle for a multifunction printing machine in accordance with the present invention; FIG. 2 is a front view thereof;

FIG. 3 is a cross-sectional view taken along line 3-3 in FIG. 2; and,

FIG. 4 is a cross-sectional view taken along line 4-4 in FIG. 2.

The broken lines in the drawings depict environmental subject matter, are for illustrative purposes only and form no part of the claimed design. The region between the break lines forms part of the claimed invention.

1 Claim, 4 Drawing Sheets(56)
